ABSTRACT OF THE DISCLOSURE

A combined hydrofining-desulfurizing-reforming system is brought on stream rapidly when processing a feed boiling in the range from 150° to 450° F. and containing substantially no C₃—C₅ hydrocarbons, by introducing makeup C₃—C₅ hydrocarbons to the hydrofining zone or desulfurizing zone and permitting the C₃—C₅ hydrocarbons to be refluxed in the desulfurizing zone.

BACKGROUND OF THE INVENTION**Field**

The present invention relates to a startup procedure for a refining process involving a hydrofining zone, a desulfurizing zone and a reforming zone.

Prior art

Reforming of naphtha feeds to produce high-octane gasoline components is well known in the petroleum art. Generally the feed to a reforming zone is hydrofined in a hydrofining zone to reduce the sulfur impurities prior to contact with the catalyst in the reforming zone. The feed from hydrofining zone is generally fractionated in a desulfurizing-fractionating zone to separate produced H₂S and water from the naphtha which is to be reformed.

The startup of such a combined hydrofining-desulfurizing-reforming system has in the past generally involved up to a week or more. This delay in bringing the system to full severity results in the loss of valuable high-octane gasoline products.

SUMMARY OF THE INVENTION

The combined hydrofining-desulfurizing-reforming system can be rapidly brought on stream and operated at a high severity by the injection of C₃—C₅ hydrocarbons into the feed to the hydrofining zone or the feed stream to the desulfurizing zone. The C₃—C₅ hydrocarbons are thereby refluxed in the desulfurizing zone, which permits the efficient removal of water from the feed which is subsequently passed to the reforming zone. This efficient removal of water permits the reforming zone to be brought to high severity, that is, to reaction conditions wherein greater than 90 F-1 clear gasoline can be produced, in a matter of several hours. Without the injection of the C₃—C₅ hydrocarbons, the startup period of time would be several days to a week or more.

BRIEF DESCRIPTION OF THE DRAWING

The present invention will be more fully explained hereinafter by reference to the figure which is a flow scheme of a hydrofining-desulfurizing-reforming system.

DESCRIPTION OF THE INVENTION

The combined process which is started up by the method of the present invention is basically a hydrofining zone; a desulfurizing-fractionating zone having a reflux stream wherein light gases are removed from the upper portion of the desulfurizing-fractionating zone, cooled

2

and returned to the desulfurizing-fractionating zone; and a reforming zone.

Sulfur impurities in the feed to the hydrofining zone are therein converted to H₂S. The reaction conditions in the hydrofining zone are generally operated at conditions resulting in substantially no cracking of the hydrocarbon feed to C₅-products. The effluent from the hydrofining zone is thereafter treated in the desulfurizing-fractionating zone to separate H₂S and water from the hydrocarbon material. The hydrocarbon material, having little or no H₂S therein and being reduced in water content, is removed from the desulfurizing-fractionating zone and contacted in the reforming zone at reforming conditions to produce a high-octane gasoline product. In the reforming zone, particularly as the severity is increased, some light gas production, as well as hydrogen production, occurs. The effluent from the reforming zone is thus treated to recover hydrogen and light gases, primarily C₃—C₅ hydrocarbons, from the gasoline stream, and a portion of this hydrogen stream containing C₃—C₅ hydrocarbons is recycled to the hydrofining zone to supply the necessary hydrogen therefor.

The reforming zone may consist of one reactor or several reactors containing a hydrogenation-dehydrogenation catalyst. Preferably the reforming zone will comprise several reactors, preferably at least three reactors, in series. The hydrocarbon feed is preheated and mixed with hydrogen and then passed through the plurality of reaction zones containing catalyst. Generally in all but the last stages the reactions are endothermic; hence they hydrocarbon feed passing between each reaction zone is reheated to the desired conversion temperature. Reformed hydrocarbons are recovered from the terminal reactor and hydrogen is separated therefrom and a portion of the hydrogen recycled to the reforming reaction zones.

Reforming of the naphtha feedstock is generally accomplished at reaction conditions including a temperature within the range of from 600° to 1100° F., preferably from 750° to 1050° F. The pressure will generally vary from atmospheric to superatmospheric, preferably within the range from 25 to 1000 p.s.i.g., and preferably from 50 to 750 p.s.i.g. The temperature and pressure can be correlated with the liquid hourly space velocity (LHSV) to favor any particularly desirable reforming reactions, as, for example, aromatization or isomerization or dehydrogenation. In general, the liquid hourly space velocity will be from 0.1 to 10, and preferably from 1 to 5.

The reforming process is conducted in the presence of hydrogen. Hydrogen may be introduced from an extraneous source, e.g., pure hydrogen from bottles may be used. Thus, the hydrogen may be used only on a once-through basis. Inasmuch as reforming generally results in the production of hydrogen, hydrogen produced in the reaction may be separated from the reformat and recycled to the reaction zone, e.g., the first reactor in a series of reactors. Thus, extraneous hydrogen need not necessarily be added to the reforming process. However, if desired, extraneous hydrogen can be used at some stage of the operation, as, for example, during startup. Regardless of the source of the hydrogen, the hydrogen can be introduced into the feed prior to contact with the catalyst or can be contacted with the catalyst simultaneously with the introduction of feed to the reaction zone. The hydrogen need not necessarily be pure hydrogen, but may contain light hydrocarbon gases in admixture therewith. Generally, when hydrogen is recirculated to the reaction zone, light hydrocarbon gases will be recirculated with the hydrogen. It is preferred that relatively pure hydrogen be used; however, difficulty and expense in purifying recycle hydrogen often prevents this from being the case. Hydrogen is preferably introduced into the reforming zone

at a rate which varies from 0.5 to 20 moles of hydrogen per mole of feed.

The reforming conditions, as is obvious, will vary depending on the feed used, whether highly aromatic, paraffinic or naphthenic, and upon the desired octane rating of the product. Generally, it is preferred that the reforming process be operated at high severity conditions, that is, conditions which will result in the production of a gasoline product having at least 90 F-1 clear octane rating, and preferably 95 F-1 clear octane rating. Reforming at low severity, that is, at conditions which result in the production of gasoline of less than about 90 F-1 clear octane rating, are generally necessary during the early periods of reforming, that is, when the feed is first being contacted with the reforming catalyst. As will be described further hereinafter, when the water content of the feed to the reforming zone exceeds about 30 p.p.m., it is very desirable that the reforming conditions be operated at low severity. Stated another way, when the partial pressure of water in the reaction zone is greater than about 0.02 p.s.i.a. (or, when the water content in the hydrogen recycle stream is greater than about 100 parts per million) and the severity of reforming is high, unfavorable sintering of the catalyst metal components occurs. Also, presence of excessive water at high severity conditions results in the removal of large amounts of halide from the catalyst, thereby rendering the catalyst less acidic than desired. As long as low severity conditions prevail, excessive water is not too detrimental to the catalyst.

The catalyst which finds use in reforming comprises a platinum group component associated with a porous solid carrier. Preferably the catalyst comprises a platinum group component, e.g., platinum, palladium, iridium, ruthenium, etc., supported with a porous inorganic oxide as, for example, alumina. The platinum group component will be present in an amount of from 0.01 to 3 weight percent and preferably 0.01 to 1 weight percent. The weight percent of a platinum group component is calculated as the metal regardless of the form in which it exists on the catalyst. The platinum group component embraces all the members of Group VIII of the Periodic Table having an atomic weight greater than 100 as well as compounds and mixtures of any of these. Platinum is the preferred component because of its better reforming activity.

Porous solid carriers which find particular use for reforming are generally the inorganic oxides, particularly inorganic oxides having surface areas of 50 to 750 m.²/gm., preferably 150 to 750 m.²/gm. The carrier can be a natural or a synthetically-produced inorganic oxide or combination of inorganic oxides. Typical acidic inorganic oxide supports which can be used are the naturally occurring aluminum silicates, particularly when acid treated to increase the activity, and the synthetically-produced cracking supports, such as silica-alumina, silica-zirconia, silica-alumina-zirconia, silica-magnesia, silica-alumina-magnesia, and crystalline zeolitic aluminosilicates.

It is generally preferred that the catalysts have low cracking activity, that is, have limited acidity. Thus, it is particularly preferred that alumina be present. Any of the forms of alumina suitable as a support for reforming catalysts can be used, e.g., gamma-alumina, eta-alumina, etc. Furthermore, alumina can be prepared by a variety of methods for purposes of this invention. Thus, the alumina can be prepared by adding a suitable alkaline agent such as ammonium hydroxide to a salt of aluminum, such as aluminum chloride, aluminum nitrate, etc., in an amount to form aluminum hydroxide which on drying and calcining is converted to alumina. Alumina can also be prepared by the reaction of sodium aluminate with a suitable reagent to cause precipitation thereof with the resulting formation of aluminum hydroxide gel. Also, alumina can be prepared by the reaction of metallic aluminum with hydrochloric acid, acetic acid, etc., in order to form a hydrosol which can be gelled with a suitable precipitating

agent, such as ammonium hydroxide, followed by drying and calcination.

Other components in addition to the platinum group component can be present with the porous solid carrier. It is particularly preferred that rhenium be present, for example, in an amount of from 0.01 to 5 weight percent and more preferably 0.01 to 2 weight percent. Regardless of the form in which rhenium exists on the catalyst, whether as metal or compound, the weight percent is calculated as the metal. Rhenium significantly improves the yield stability of the platinum-containing catalyst, that is, a process using a platinum-rhenium catalyst has a significantly lower yield decline throughout the reforming process than a catalyst comprising platinum without rhenium. The platinum-rhenium catalyst is more fully described in U.S. Pat. 3,415,737, which is incorporated herein by reference thereto.

The catalyst comprising the platinum group component can be prepared in a variety of methods; that is, the platinum group component can be associated with the porous solid carrier by impregnation, ion-exchange, coprecipitation, etc. Generally it is preferred to incorporate the platinum group component by impregnation. When rhenium is incorporated along with the platinum group component, the rhenium component can also be associated with the carrier by various techniques, e.g., impregnation, ion-exchange, coprecipitation, etc. Preferably, the platinum group component and rhenium component are associated with the carrier by impregnation, either simultaneously or sequentially. Particularly preferred platinum group compounds for use in impregnation include chloroplatinic acid, ammonium chloroplatinates, polyammineplatinum salts, palladium chloride, etc. Suitable rhenium components are perrhenic acid, ammonium or potassium perrhennates, etc.

The catalyst used in reforming will preferably be promoted by the addition of halides, particularly fluoride or chloride. Bromides may also be used. The halides provide a limited amount of acidity to the catalyst which is beneficial to most reforming operations. A catalyst promoted with halide preferably contains from 0.1 to 3 weight percent total halide content. Halides can be incorporated onto the catalyst carrier at any suitable stage of catalyst manufacture, e.g., prior to or following incorporation of the platinum group component and/or the rhenium component. Halide can also be incorporated onto the catalyst during incorporation of the platinum group component or rhenium component.

The hydrofining zone used in the combined process is generally operated at hydrofining conditions including a temperature of from 700° to 900° F., preferably from 700° to 850° F. Generally the pressure will fall within the range from 200 to 2000 p.s.i.g., preferably 200 to 1000 p.s.i.g. The liquid hourly space velocity generally will be from 1 to 5, and the hydrogen/feed ratio will generally be from 1000 to 5000 or more s.c.f. hydrogen per barrel of feed. The reaction conditions are generally severe enough to convert substantially all the organic sulfur to hydrogen sulfide; thus the reaction conditions should be severe enough so that the effluent from the hydrofining zone contains less than about 10 p.p.m. organic sulfur, preferably less than about 1 p.p.m. organic sulfur. Generally the feed to the hydrofining zone will not contain substantial amounts of organic nitrogen; however, when nitrogen is present the organic nitrogen content may be reduced with the concurrent production of ammonia. The hydrofining reaction conditions should be such that substantially no cracking of the feed occurs. Thus, there should be substantially no C₅-production. Any cracking represents the loss of valuable gasoline-forming materials. By "substantially no cracking" is meant that less than about 5 weight percent, preferably less than about 2 weight percent, of the feed is converted to C₅-product (i.e., to C₅ or lower boiling hydrocarbons).

The catalyst which finds use in the hydrofining zone will generally be cobalt-molybdenum, nickel-molybdenum or nickel-cobalt-molybdenum, supported on an alumina carrier or a zeolite carrier (for example, zeolite X, Y, L). Other supports or carriers may be used, e.g., silica, silica-alumina, magnesia, etc. A preferred catalyst for hydrofining or hydrodesulfurizing is an alumina-containing support with a minor portion of molybdenum oxide and cobalt oxide. The catalyst can be pretreated with hydrogen sulfide prior to contact with hydrogen and feed.

The desulfurizing-fractionating zone which finds use in the present invention is well known in the prior art. Basically the zone comprises a fractionation or distillation column having a series of plates or trays over which vapors rise toward the top of the column and liquid circulates downwardly. A stream is removed from the bottom of the column, reheated and returned to the bottom portion of the column. This provides the necessary heat input for operation of the system. If desired, a heating column could be placed at the bottom of the desulfurizing-fractionating column. The column is designed so that light gases, that is, H_2S , water, and any light hydrocarbon gases boiling below the C_5 range are removed from the top of the column. A portion of the light hydrocarbon gases thus removed is cooled and returned as liquid to the top portion of the column to provide the necessary reflux liquid. Unless a sufficient amount of light hydrocarbon gases, particularly C_3-C_5 hydrocarbons, are refluxed, the efficiency of the column for removing H_2S and water is decreased. It is obvious that inasmuch as the vapors leaving the top are cooled and returned as liquid to the column, only the hydrocarbon gases of the C_3-C_5 boiling range are effective reflux material. The difficulty in converting methane and ethane to a liquid removes these gases as possible choices.

The hydrocarbon effluent from the desulfurizing-fractionating zone which is substantially free of H_2S and water and light hydrocarbon gases is then passed to the reforming zone. Unless the desulfurizing-fractionating zone is properly refluxed, water will not be removed in substantial amounts.

The present inventive startup procedure disclosed and claimed herein is valuable when processing feeds boiling within the range from $150^{\circ}-450^{\circ}$ F. and containing substantially no light hydrocarbon gases (i.e., less than about 1 weight percent). The feeds boiling within the naphtha range may be straight-run naphthas or thermally cracked or catalytically cracked naphthas or blends thereof. The present invention is particularly useful when the feed to the hydrofining zone contains organic sulfur compounds in an amount of at least 100 p.p.m. and water or compounds which will form water in an amount of at least 50 p.p.m. The feed to the reforming zone should contain less than about 10 p.p.m., more preferably less than 1 p.p.m., sulfur, either organic sulfur or H_2S , etc. Thus the hydrofining zone must convert substantially all of the organic sulfur in the feed to H_2S , and the desulfurizing-fractionating zone must operate efficiently enough to remove substantially all the H_2S from the feed. Also, inasmuch as the reforming zone cannot be brought to high severity until the water content in the feed to the reforming zone is less than about 30 p.p.m., it is necessary that the desulfurizing-fractionating zone remove substantially all the water therein. Any compounds which will form water are generally converted to water in the hydrofining zone.

As indicated previously, the reformer must be operated at low severity until the water content to the feed in the reformer is low, that is, below about 30 p.p.m. The desulfurizing-fractionating zone which removes water in the feed from the hydrofining zone operates efficiently only if adequately refluxed with C_3-C_5 hydrocarbons. But since the hydrofining zone is operated at conditions wherein substantially no cracking occurs and the feed

originally contains no C_3-C_5 hydrocarbons, a difficulty is presented as far as adequately refluxing the desulfurizing-fractionating zone. Generally when the combined system is operating at high severity, that is, particularly when the reforming zone is operating at high severity 5 C_3-C_5 hydrocarbons are produced in the reforming zone and are recycled to the hydrofining zone and thence to the desulfurizing-fractionating zone. However, the reforming zone does not produce substantial amounts of C_3-C_5 hydrocarbons until high severity is reached, and high severity cannot be reached until the water content 10 in the feed is reduced; thus, the end result is normally a slow startup procedure, requiring up to a week or more before sufficient C_3-C_5 hydrocarbons are recycled from the reforming zone to the hydrofining zone and thence to the desulfurizing-fractionating zone, thereby allowing adequate refluxing of the desulfurizing-fractionating zone to take place.

The slow startup procedure of the prior art can be 20 considerably shortened by the addition of makeup C_3-C_5 hydrocarbons either to the feed to the hydrofining zone or to the feed to the desulfurizing-fractionating zone.

Thus the addition of hydrocarbons boiling in the range 25 of C_3-C_5 hydrocarbons in the amount of from 1 to 10 weight percent, based on the total hydrocarbon feed to the hydrofining zone, will permit rapid startup of the over-all process. The excess C_3-C_5 hydrocarbons are refluxed in the desulfurizing-fractionating zone, thereby permitting efficient removal of water from the feed to the reforming zone. By C_3-C_5 hydrocarbons, it is 30 meant to include such hydrocarbons as propane, butane, isobutane, pentane, isopentane, etc., or mixtures thereof.

The process of the present invention will be better understood by reference to the diagram in the figure. The 35 diagram shows a typical combined hydrofining/desulfurizing-fractionating/reforming system wherein the present invention is applicable. A naphtha feed boiling within the range of from $150^{\circ}-450^{\circ}$ F. and containing at least 100 p.p.m. organic sulfur compounds and at least 50 p.p.m. water (or compounds which will form water) and containing substantially no C_3-C_5 hydrocarbons is introduced through line 1, in contact with hydrogen from line 2, thence through line 3 to furnace 4. The naphtha feed and hydrogen are heated in furnace 4 to hydrofining reaction conditions and are then passed by line 5 into hydrofining reaction zone 6 containing hydrofining catalyst 7, preferably a cobalt oxide-molybdenum oxide-alumina catalyst. In the hydrofining zone 6 the organic sulfur compounds are converted to H_2S ; also any compounds which will form water are converted to water at the reaction conditions. The total effluent from hydrofining zone 6 is 40 passed by line 8 to separation zone 9. In separation zone 9 hydrogen is removed by line 10 and the hydrocarbon feed containing the H_2S and H_2O is passed by line 11 to desulfurizing-fractionating column 12.

The light hydrocarbons, that is the hydrocarbons boiling 45 in the C_3-C_5 range and lower, plus H_2S and water are removed from the top of the desulfurizing-fractionating column 12 by line 13, cooled in heat exchanger 14, then 50 passed by line 15 to separation zone 16. Light gases such as methane and ethane, H_2S and water, are removed by line 17; the heavier hydrocarbons, that is, the C_3-C_5 hydrocarbons, are returned as liquid by line 18 to the desulfurizing-fractionating column 12.

From the bottom of desulfurizing-fractionating column 55 12 heavy hydrocarbons, that is, hydrocarbons boiling from C_5 and above, are removed by line 19. A portion of the heavier hydrocarbons is generally returned to the desulfurizing-fractionating column 12 by line 20 through furnace 21 and line 22. This reflux of heavy hydrocarbons provides sufficient heating to operate the column, i.e., to permit vaporization of at least part of the liquid moving down the column.

The purified effluent from desulfurizing-fractionating 60 column 12 is passed by line 19 to reforming furnace 23.

Hydrogen may be added to the feed at this stage as desired (not shown). The feed exiting from furnace 23 by line 24 will generally be at the temperature for reforming. The feed is passed to the reforming reactor 25 and contacted with a hydrogenation-dehydrogenation catalyst 26. Preferably the catalyst comprises a platinum group component, particularly platinum in association with alumina. The preferred catalyst is platinum-rhenium associated with alumina. In reforming reactor 25 the hydrocarbon naphtha is reformed to high octane gasoline components which is removed by line 27 and passed to separator 28. In separator 28 hydrogen and light gases which were produced in reforming reactor 25 are separated from the gasoline boiling range materials.

The gasoline product is passed from separator 28 by line 29 to debutanizer 31 wherein a high-priority product stream is removed by line 31 and a light gas stream is removed by line 32.

The hydrogen and light hydrocarbons, particularly the C₃-C₅ hydrocarbons, recovered from separator 28 are passed by line 33, admixed with the hydrogen from line 10, and thence by line 2 to admixture with the naphtha feed to the hydrofining zone. A portion of the hydrogen gas recovered in separator 28 may be bled off by line 34 and used as a fuel or used in a hydrocracking zone, etc.

During startup of the present combined process and until sufficient C₃-C₅ hydrocarbons are produced in the reforming zone for recycle to the hydrofining zone and desulfurizing-fractionating zone, makeup C₃-C₅ hydrocarbons can be introduced into desulfurizing-fractionating zone 12 or into the reflux system or at any convenient point before the desulfurizing-fractionating zone 12. It is particularly preferred that the makeup C₃-C₅ hydrocarbons be introduced into the feed to the hydrofining zone, for example by line 35. At least 1 to 10 weight percent C₃-C₅ hydrocarbons, based on the total feed, can be introduced, based on the total feed, can be introduced by line 35. Alternately, C₃-C₅ hydrocarbons can be added to the feed from the hydrofining zone, e.g., via line 36.

If more hydrocarbon feed is hydrofined than can be used in the reforming zone, the excess hydrofined feed can be stored for a period of time. The excess feed may then later on be added to the stream to the desulfurizing-fractionating zone as a makeup hydrofined hydrocarbon stream (not shown in the figure). The C₃-C₅ hydrocarbons can be introduced with this makeup hydrofined hydrocarbon stream, if desired.

The foregoing description of this invention is not to be considered as limiting since many variations can be made by those skilled in the art without departing from the spirit or scope of the appended claims.

What is claimed is:

1. In a combined hydrofining-reforming system:

wherein a hydrocarbon feed boiling within the range from 150°-450° F. (and containing substantially no C₃-C₅ hydrocarbons) and containing organic sulfur compounds in an amount of at least 100 p.p.m. and water or compounds which will form water in an amount of at least 50 p.p.m. is contacted in a hydrofining zone at hydrofining conditions and in the presence of hydrogen with a catalyst to convert organic sulfur compounds to H₂S with substantially no cracking to C₅ product, and the effluent from the hydrofining zone is treated in a desulfurizing-fractionating zone to separate H₂S and water from the hydrocarbon material, and a reflux stream of light gases is removed from the upper portion of the desulfurizing-fractionating zone, cooled and returned to the desulfurizing-fractionating zone, and the effluent (hydrocarbon material) from the desulfurizing-fractionating zone is contacted in a reforming zone at reforming conditions and in the presence of hydrogen with a reforming catalyst to produce a product of high octane rating, and the effluent from the reforming zone is separated into at least a hydrogen stream normally containing C₃-C₅ hydrocarbons and a gasoline stream, at least a portion of the hydrogen stream being recycled to the hydrofining zone,

the improvement for rapidly bringing the combined process onstream which comprises introducing makeup C₃-C₅ hydrocarbons to the feed to the hydrofining stream or to the feed to the desulfurizing-fractionating zone, and permitting the C₃-C₅ hydrocarbons to be refluxed, the weight percent of C₃-C₅ hydrocarbons to total hydrocarbon feed being from 1 to 10.

2. The process of claim 1 wherein said reforming catalyst comprises platinum in association with the porous solid carrier, said platinum being present in an amount from 0.01 to 3 weight percent.

3. The process of claim 1 wherein the product of high octane rating from the reforming zone has an octane number of at least 90 F-1 clear octane.
